FINISH GRINDING MECHANISM

Karl Rabe, Stuttgart, Germany, assignor to Dr. Ing. h. c. F. Porsche, K.-G., Stuttgart-Zuffenhausen, Germany, a company of Germany

Application November 26, 1937, Serial No. 176,563
In Germany November 28, 1936

9 Claims. (Cl. 51—105)

This invention relates to a finish grinding mechanism, and more particularly is directed to an arrangement for the finish grinding of cams or other irregular shapes.

5 An object of my invention is the provision of an economical and simple means for the finish grinding of regular or irregular shapes.

Another object of my invention is the provision of means for the direct finish grinding of 10 cams or other irregular shapes.

Another object of this invention is the provision of means for the finish grinding of cams or other irregular shapes directly from a controlling diagram.

15 A more specific object of this invention is the provision of an arrangement for the accurate finish grinding of control cams directly from a valve-lift diagram.

These and other features of the invention will 20 be best understood and appreciated from the following description of a preferred embodiment thereof, described for purposes of illustration and shown in the accompanying drawing in which:

The single figure shows a side elevation partially in cross-section and partially diagrammatically of a preferred arrangement for carrying out this invention.

As indicated in the drawing, I preferably provide a pair of bearings 10 and 11 for journaling 25 a shaft 12, to one end of which is connected by any suitable means a disk 13. A handle 14 is provided on the disk 13 for rotating the said disk together with the shaft 12. The latter is preferably threaded along the major portion of its 30 length and a nut 15 engages said thread for movement along the shaft. The nut 15 may be provided with a bore 16 for the journaling of slides which are slotted to receive the lower end of a forked lever 17. The upper end of the lever 35 17 is rigidly attached as by means of a key to a shaft 18 journaled for rotation about a fixed axis in a frame or other means not shown. A second lever 19 is likewise fixedly attached to the shaft 18 at one end, while on its other end the lever 40 19 has a grinding wheel 20 journaled for rotation thereon.

It will be seen from a study of the parts indicated above, that upon turning the handle 14 the shaft 12 will rotate in bearings 10 and 11. 45 Such rotation will move the nut 15 longitudinally along the shaft, thereby rotating the lever arm 17 about the axis of shaft 18. This results in a rotary movement of the lever arm 19 together with the grinding wheel 20, so that as viewed in 50 the drawing, the grinding wheel 20 will move

about the axis of the shaft 18 upwardly or downwardly in a vertical plane. As the disk 13 is adapted to have suitable indicia thereon which may take the form of a direct scale, movement of the grinding wheel 20 can be controlled directly as desired by alignment of the proper scale reading with the fixed index 21. In case of fine work the index 21 may take the form of a reading microscope as illustrated, whereby the position of the grinding wheel 20 may be very accurately 10 controlled.

The grinding wheel 20 is adapted to operate upon a suitable work-piece indicated in this case as a cam 22. The cam is adapted to be placed upon a rotatable support 24 and attached thereto 15 in any suitable manner. The support 24 is provided preferably upon its periphery with a plurality of ratchet teeth engaged by means such as a pawl 23. The pawl 23 is preferably pivoted about a fixed bearing block 28 and is adapted 20 to be moved by a handle 25 connected to one end of the pawl through a rod 30. The pawl 23 has been illustrated as consisting of a double lever having a spring pressed tooth at one end thereof engaging the ratchet teeth. A second pawl 29 25 is adapted to engage the ratchet teeth in an opposite sense from that of the pawl 23 in order to prevent reverse movement of the member 24. It will be seen that upon movement of the handle 25 inwardly, the engaging end of the pawl 23 will 30 move in the direction indicated by the arrow to ratchet along the member 24, thereby shifting the position of the work-piece 22 relative to the grinding wheel 20. In order to indicate the number of notches moved there may be provided a 35 counter 27 engaged by a lug 26 on the rod 30, so arranged that upon each inward movement of the rod 30, the counter will advance one position.

It will be seen from the above description that by means of this invention, a simple and accurate 40 grinding of the cam may be brought about. All of the control members are adapted to be positioned so as to be readily handled by one operator who, at the same time, may be accurately adjusting the position of the grinding wheel by 45 examining the scale through the reading microscope. By means of this arrangement, it is possible to grind cams or other shapes directly from a control diagram without the necessity of first forming a control cam by laborious methods. 50 The invention has been found to be particularly advantageous in the direct transfer of the dimensions of a valve-lift diagram to the formation of the desired control cam.

It is obvious that my invention is not limited to 55

the construction illustrated. Any equivalent linkage means could be utilized for the movement of the grinding wheel. The scale need not be positioned in a plane at right angles to the 5 axis of the shaft, but in any other suitable manner. The rotation of the work-piece could be brought about by means other than the pawl and ratchet illustrated; for example, a worm gearing arrangement could be used. If the pawl and 10 ratchet arrangement is retained, it is also within the comprehension of this invention that the pawl could be actuated electro-magnetically as well as by hand. It is to be understood, therefore, that the scope of this invention is only limited as indicated in the claims which follow: 15

I claim:

1. In a grinding mechanism, in combination, a shaft, means for journaling said shaft, threads on said shaft intermediate said journaling means, 20 a nut mounted on said threads for movement along said shaft, an arm pivotally and slidably connected to said nut at one end and pivotally mounted about a fixed axis at its other end, a second arm mounted for pivotal movement with 25 said first arm about said fixed axis, a grinding wheel rotatably mounted on said second arm, rotatable means adapted to support a work-piece in operable relation with said grinding wheel, ratchet teeth on said supporting means, a first pawl, 30 means for actuating said pawl for rotating said supporting means, a second pawl for preventing movement of said supporting means in a direction opposite to that produced by said first pawl, a scale mounted for rotation with said shaft, 35 fixed means in co-operative relationship with said scale for determining the position of said grinding wheel, whereby upon movement of said shaft said grinding means may be moved to desired positions as observed upon said scale and said rotatable supporting means may be rotated simultaneously by said pawl means so that said work piece may be ground to any desired contour.
2. The combination according to claim 1, in combination with a counter, and means on the said 45 pawl actuating means for engaging said counter, whereby the relative rotary position of said work supporting means can be determined from said counter.
3. The combination according to claim 1, in combination with means actuated upon rotation of said work supporting means for indicating the 50 position of said work piece.
4. The combination according to claim 1, in which said first pawl is mounted for rotation about a fixed axis, and the means for actuating said pawl comprises a lever pivotally connected to said pawl.
5. In a grinding mechanism, in combination, a shaft, means for journaling said shaft, threads 60 on said shaft intermediate said journaling means, a nut mounted on said threads for movement along said shaft, an arm pivotally and slidably connected to said nut at one end and pivotally mounted about a fixed axis at its other end, a second arm mounted for pivotal movement with 65 said first arm about said fixed axis, a grinding wheel rotatably mounted on said second arm, rotatable means adapted to support a work-piece in operable relation with said grinding wheel, a 70 scale mounted for rotation with said shaft, fixed

means in co-operative relationship with said scale for determining the position of said grinding wheel, whereby upon movement of said shaft said 5 grinding means may be moved to desired positions as observed upon said scale and said rotatable supporting means may be rotated simultaneously by said pawl means so that said work piece may be ground to any desired contour.

6. In a machine for producing continuous irregular contours on a work piece, means for supporting said work piece for rotation about an axis, manually controlled means for at will imparting increments of rotary movement to said work piece about its axis, a material removing tool, a support therefor, manually controlled means for moving said support and tool in and out with respect to said axis, scale means for indicating the position of said tool relative to the axis of said work piece, and an indicator for showing the extent of rotative movement given to 20 said work piece, said work piece rotating means and said tool moving means being movable alternately.

7. In a machine for producing continuous irregular contours on a work piece, means for supporting said work piece for rotation about an axis, 25 manually controlled means for at will imparting increments of rotary movement to said work piece about its axis, including a ratchet and a pawl drive mechanism, a counter to count and indicate 30 the number of steps the work piece has been rotated, a material removing tool, a support therefor, manually controlled means for moving said support and tool in and out with respect to said axis, and scale means for indicating the position 35 of said tool relative to the axis of said work piece, said work piece rotating means and said tool moving means being movable alternately.

8. In a machine for producing continuous irregular contours on a work piece, means for supporting said work piece for rotation about an axis, manually controlled means for at will imparting increments of rotary movement to said work piece about its axis, including a ratchet and a pawl drive mechanism and a counter to 40 count and indicate the number of times the ratchet and pawl mechanism has been actuated, a material removing tool, a support therefor, manually controlled means for moving said support and tool in and out with respect to said axis, and scale means for indicating the position of 45 said tool relative to the axis of said work piece, said work piece rotating means and said tool moving means being movable alternately.

9. In a machine for producing continuous irregular contours on a work piece, means for supporting said work piece for rotation about an axis, manually controlled means for at will imparting increments of rotary movement to said work piece about its axis, a material removing tool, a support therefor, manually controlled means for moving said support and tool in and out with respect to said axis, said work piece rotating means and said tool moving means being movable alternately, and position indicating 55 mechanism on the means for moving the tool and the means for rotating the work piece, whereby a predetermined design of said work piece may be plotted and followed.
